COMBINED MIRROR AND LIPSTICK HOLDER

Benita E. McCormick, Chicago, Ill.

Application March 7, 1957, Serial No. 45,137

Term of patent 3½ years

(Cl. D86—10)

Fig. 1.

Fig. 2.

Fig. 3.

Fig. 4.

Fig. 5.

Fig. 1 is a front elevational view of the combined mirror and lipstick holder illustrating my new design;

Fig. 2 is a rear elevational view of the combined mirror and lipstick holder shown in Fig. 1;

Fig. 3 is an edge elevational view of the same which appears identical when viewed from either edge thereof;

Fig. 4 is a plan view of the same; and

Fig. 5 is a transverse cross sectional view of the handle portion of the same as viewed along the plane of the line 5—5 in Fig. 1 thereof.

I claim:

The ornamental design for a combined mirror and lipstick holder, substantially as shown.
